DESIGN FOR A SHOE

Josephine Davies, New York, N. Y., assignor to Bancroft-Walker Company, Waltham, Mass., a corporation of Massachusetts

Application July 18, 1936, Serial No. 63,915

Term of patent 3½ years

To all whom it may concern:

Be it known that I, Josephine Davies, a citizen of the United Kingdom of Great Britain, residing at New York, in the county of New York and State of New York, have invented a new, original, and ornamental Design for a Shoe, of which the following is a specification, reference being had to the accompanying drawing forming a part thereof, in which,

Fig. 1 is a plan view of the shoe showing my new design,

Fig. 2 is a view of the shoe in side elevation. In both figures the rear portion and the toe portion of the shoe are shown conventionally in dotted lines, the dominant feature of the design residing in the portion shown in full lines.

I claim:

The ornamental design for a shoe substantially as shown and described.

In witness whereof, I have affixed my signature hereto.

JOSEPHINE DAVIES.
